(57) **CLAIM**

The ornamental design for an oven rack pull and push spatula, as shown and described.

DESCRIPTION

FIG. 1 is a perspective view of a oven rack pull and push spatula, showing the new design;

FIG. 2 is an alternate perspective view thereof;

FIG. 3 is a top plan view thereof;

FIG. 4 is a left-side elevational view thereof, the right-side elevational view being a mirror image thereof;

FIG. 5 is a bottom plan view thereof;

FIG. 6 is a front elevational view thereof; and,

FIG. 7 is a rear elevational view thereof.

The broken lines showing a oven, arm, and spatula handle in FIG. 1, a spatula handle in FIGS. 2-5 and 7, and spatula head apertures in FIGS. 1-3 and 5-7 are included for the purpose of illustrating the invention in use, and form no part of the claimed design.
